[57] CLAIM

The ornamental design for an apparatus for cutting by melting, substantially as shown and described.

DESCRIPTION

FIG. 1 is a front view of apparatus for cutting by melting showing the new design;

FIG. 2 is a rear view thereof;

FIG. 3 is a side view taken from the right of FIG. 1;

FIG. 4 is a side view taken from the left of FIG. 1;

FIG. 5 is a top view thereof; and

FIG. 6 is a bottom view thereof.

FIG. 1

FIG. 2

FIG. 3

FIG. 4

FIG. 5

FIG. 6
